UNITED STATES PATENT OFFICE.

CLARENCE H. HOWARD, OF ST. LOUIS, MISSOURI, ASSIGNOR TO DAVIS LOCOMOTIVE WHEEL COMPANY, OF ST. LOUIS, MISSOURI, A CORPORATION OF DELAWARE.

LOCOMOTIVE PILOT-BEAM.

No. 859,296.

Specification of Letters Patent.

Patented July 9, 1907.

Application filed April 27, 1907. Serial No. 370,837.

To all whom it may concern:

Be it known that I, CLARENCE H. HOWARD, a citizen of the United States, residing at St. Louis, in the State of Missouri, have invented a new and useful Improvement 5 in Locomotive Pilot-Beams, of which the following is a specification.

My invention relates to a locomotive end-sill or pilot-beam, and is in the nature of an improvement on the Letters Patent granted to Westlake and Thomas, 10 February 19, 1907, number 844,765, for an improvement in locomotive engine frames, in which the end-sill is formed with a rearwardly projecting bracket between the longitudinal beams of the engine frame, combined with webs depending from the said sill and 15 bracket and forming therewith a housing for draft-gear.

My invention has for its object, to dispense with the separately constructed coupler-pocket and its braces ordinarily attached to the front side of the end-sill for 20 a short shank coupler, also to enable an ordinary coupler to be used for overhanging the pilot sufficiently to prevent interference therewith when coupling the engine to a car or other rolling stock, and to increase the strength and rigidity of the end-sill or pilot-beam. 25 The invention consists in features of novelty as hereinafter described and claimed, reference being had to the accompanying drawing forming part of this specification, whereon,

Figure 1, is a top plan view of a preferable form of 30 my improved locomotive end-sill or pilot-beam; Figs. 2 and 3, a front and end elevation thereof respectively, and Fig. 4, a vertical longitudinal section through the end-sill on line 4-4, in Fig. 1.

Like letters and numerals of reference denote like 35 parts in all the figures.

a represents my improved end-sill or pilot-beam, which excepting the parts thereof forming my invention, is preferably, substantially similar to the end-sill described in the said patent, having its body-portion 40 1, preferably box-shaped in cross section, with its top and bottom walls parallel, but in the present case intersected transversely at the middle for a suitable distance from the top wall by a box-shaped portion 2 of reduced depth, which forms a space thereat beneath 45 the bottom of the portion 2 and that of the divided parts of the main body-portion 1, the box-shaped portion 2 projecting for a suitable distance from the front side of the body-portion 1 and forming a dead-block to the end-sill *a*; the whole with its combined adjuncts 50 as hereinafter referred to, being composed preferably, of cast steel integral throughout; but the body-portion 1 may be of any other suitable shape in cross section, such as channel, I, or T-shaped, and either straight longitudinally at the top and bottom as shown, or

otherwise, and with or without the reduced middle portion 2 as desired. The end-sill *a* is adapted to bear at its rear side against the ends of the longitudinal metallic beams *b* of the engine frame, as indicated by dotted lines, and in the present case is formed on its rear side between the beams *b*, with a bracket *c* adapted to bear laterally against the inner faces of the beams *b* to which it is firmly fixed, and having an opening 3 therethrough for the upright center or pivot-post (not shown) of the pony-truck of the engine frame. Furthermore, from the underside of the end-sill *a* and bracket *c* depend two opposite and parallel upright webs 4 (one on each side of the longitudinal center of the engine frame) having upright lugs or stops 4' and otherwise adapted on their inside faces to form a pocket or housing for a suitable coupler (and combined draft-gear) as indicated by dotted lines in Fig. 1, all the said parts heretofore recited being practically the same as the corresponding parts set forth in the said patent, and therefore, needing no further description.

Projecting from the front side of the body-portion 1, preferably at the top or adjacent thereto for its entire length, or thereabout, and integral therewith, is an overhanging member *d*, comprising preferably, a horizontal web 6 which in the present case forms at its middle part the top wall of the forwardly projecting box-shaped portion 2 of the body-portion 1, and thence preferably inclines rearward to each end of the body-portion 1, the outer edge of the web 6 having preferably a depending flange 6' which forms at the middle in the present case the front end wall of the box-shaped portion 2, and thence suitably configured and inclined downward to each end of the body-portion 1 at the bottom, the whole forming a strong re-inforcing compression member to the end-sill *a* and increasing its rigidity and resistance to violent frontal shocks. Through the web 6 are preferably lightening holes 7, 7'. Or the overhanging member *d* in front of the sill *a* may be otherwise configured as found most suitable. By this construction also, the projecting box-shaped portion 2 of the body-portion 1 is strengthened and enabled to be extended outward from the body-portion 1 sufficiently to permit of using an ordinary coupler in lieu of the short shank coupler with its separately constructed pocket fixed to the sill and laterally braced thereto, and thereby enables the engine to be coupled to a car or other rolling stock without interfering with the pilot (not shown) which in the present case is fixed to the front side wall of the body-portion 1, and to brackets 8 depending therefrom.

In cases where the projecting box-shaped portion 2 of the body-portion 1 is eliminated, the overhanging member *d* may be suitably shaped and arranged at its middle portion to form a dead-block to the sill, and

if required adapted on its under portion to form a pocket or housing for a draft-gear according to various types of end-sill or pilot-beam.

I make no claim to a forward extension of the end-sill at the middle to form a dead-block thereto, but

What I claim as my invention and desire to secure by Letters Patent is:

In a locomotive end-sill or pilot-beam of the character described, the combination with the body thereof, of a

suitably shaped coupler-pocket and brace integral with, 10 and overhanging the front side of the said body at the top, or adjacent thereto, for its entire length, or thereabout, substantially as described.

In testimony whereof I have signed my name to this specification in the presence of two subscribing witnesses. 15

CLARENCE H. HOWARD.
